UNITED STATES PATENT OFFICE

PAUL O. HECHT, OF DAVENPORT, IOWA, ASSIGNOR TO B & D MFG. CO., OF ROCK ISLAND,
ILLINOIS, A CORPORATION OF ILLINOIS

AUTOMATIC THREAD-CUTTING TOOL

Application filed June 4, 1925. Serial No. 34,833.

My invention relates to means for interiorly or exteriorly threading articles, such as rods, pipes, nuts, and the like and more particularly to mechanisms of this character adapted to operate automatically, to thread such devices and remove the threading means therefrom without reversing the direction of rotation.

Among the objects of my invention are to produce a superior automatic thread cutting tool; to produce a device of the character stated which will cut threads to a definite predetermined point and then be released for withdrawal from the article being threaded; to provide an improved locking and tripping mechanism for an automatic device of the character described; to provide improved holding and guiding means having movable thread cutting elements; to provide means for moving the thread cutting elements away from the work in such a direction that there will be no scoring or damaging of the thread faces by the withdrawing cutting members; and such further objects, advantages and capabilities as will hereafter more fully appear and as are inherent in the construction disclosed herein.

My invention further resides in the combination, construction and arrangement of parts illustrated in the accompanying drawings and, while I have shown therein a preferred embodiment of my invention, I desire the same to be understood as illustrative only and not as limiting said invention.

In the drawings annexed hereto and forming a part hereof, Fig. 1 is a broken sectional elevation of what is now considered the preferred embodiment of this invention; Fig. 2 is a bottom plan view of the structure shown in Fig. 1 with part of the elements omitted; Fig. 3 is a broken longitudinal sectional elevation of this device with the tripping mechanism omitted therefrom; Fig. 4 is a transverse section substantially along the plane indicated by the line 4—4 Fig. 3; Fig. 5 is

a broken longitudinal section substantially along the broken plane indicated by the line 5—5 Fig. 6; Fig. 6 is a bottom plan view of the structure shown in Fig. 5, the same being similar to Fig. 2 but with the tripping ring 50 omitted; Fig. 7 is a bottom plan view of the chaser holding and guiding block; Fig. 8 is a lateral view of the structure shown in Fig. 7; Fig. 9 is a face view at a right angle to the view shown in Fig. 8; Fig. 10 is a bottom plan view of the holding means for holding the thread cutting elements or chasers in the guiding or chaser carrying blocks; Fig. 11 is a lateral face view of the structure shown in Fig. 10; Fig. 12 is a lateral view at 60 a right angle to Fig. 11; Fig. 13 is an elevation of one of the thread cutting elements or chasers; Fig. 14 is a plan view thereof; and Fig. 15 is a transverse section through the flange 19 and joint 21. 65

Referring more in detail to the annexed drawings, numeral 1 designates the shank of my improved tap or die head whereby this device is attached to the machine with which it is used for cutting threads. This shank 70 is provided with a flange 2 which forms a holding means for the blocks 3 which reciprocate laterally to carry the thread cutting elements 4 to open and closed position. In the construction shown, these thread cutting elements are provided with shoulders 5 and 6 which engage respectively with shoulders 7 and 8 of the guiding blocks 3. The holding blocks 9 are threaded with threads of the same pitch as the thread cutting elements and engage the threads thereof to hold these elements in properly adjusted positions. Screws 10 are passed through the blocks 9 into the guiding blocks 3 and hold all these parts properly assembled. Screws 11 abut 80 the outer ends of the blocks and hold the shoulders 5 and 6 tightly engaged with the shoulders 7 and 8, when the screws 11 are turned in to force the blocks 9 against the cutting elements. In forming the thread 85 90

cutting members 4, cylindrical bars are threaded throughout their lengths and then they are divided into two or more parts, longitudinally. From these threaded parts are formed the thread cutters.

In making the holding members 9, a ring of proper thickness and diameter is threaded interiorly and then cut along non-radial planes parallel to the axis of the ring, the 10 planes occurring in pairs arranged in parallelism and at a suitable distance from each other so that the blocks 9 will be of the proper width when smoothed and polished. The blocks should be equally spaced around 15 the ring so that, when mounted in the openings in blocks 3, the threads will occupy the same relative positions that they had in the ring.

Furthermore, by reason of the method of 20 forming the blocks or holding members 9 all cutters 4 are interchangeable. The blocks 9 must be numbered consecutively as they occur in the ring and be used in the same order when mounted in the tool as shown 25 in Fig. 6. From this it results that the threads of the cutters always line up perfectly, thus causing the cutting of perfect threads. The threads of the thread cutting elements 4 and the blocks 9 are so cut that 30 the threads of the cutters always match properly and do not misfit in the cutting operation.

The shank 1 is hollowed out as indicated 35 at 12 for the reception of the thread cutting elements 4. As will readily be appreciated, these are adjustable so that, in event they become broken off at or below the lower end of the head, they can be adjusted to the desired position, merely by loosening the proper 40 screw 11 and removing the corresponding screw 10, thus permitting removal of the block 9.

Surrounding the shank 1 is a ring 13 provided with an outwardly extending flange 14 45 which is perforated for the passage of springs 15 resting at their upper ends against the ring 16 and at their lower ends being seated in sockets 17 in the flange 2. Assuming the flange 2 to be held stationary the 50 springs 15 have a tendency to push the plate 16 upwardly against the lower end of the ring 18. This has a screw threaded engagement at 18^a with the internal flange 19 of the shell 20. Therefore, when the shell is free to 55 move, the springs 15 will cause the same to be moved upwardly relatively to the shank 1, resulting in an operation which will presently be described.

The upper end of ring 13 preferably has 60 an overlapping connection as shown at 21 with a ring 22 surrounding the shank 1, as shown most clearly in Figs. 1 and 5. The ring 22 is preferably made of hardened steel and is beveled at its upper end as shown at 65 23 to serve as a cam for actuating the dogs 24,

the latter serving as means for holding the shell 20 downwardly in its normal operating position. The dogs 24 are provided with shoulders 25 for engaging the upper edge of a ring 26 which is secured to the upper end of ring 18 by the screws 28, passing through ring 27 and into flange 29 at the upper end of ring 18. A ring 30 is secured by any desired means such as a pin 31 to the shank 1 and serves as an abutment for the upper edges of the dogs 24, as shown clearly in Fig. 1. These dogs are pressed outwardly by the spring 32 which is mounted between them in the same slot in which the dogs 24 slide in the shank 1. From this it will be seen that when the shell 20 is forced downwardly, carrying with it rings 18, 26 and 27, the spring 32 will cause the dogs 24 to move outwardly until the shoulders 25 engage above the top of ring 26 thereby locking the shell and its connected parts in lowered position. The ring 18 may be adjusted longitudinally in respect to shell 20 by loosening the set screws 33 and then turning the ring relatively to the shell. Any such adjustment will cause the dogs 24 to engage fresh portions of ring 26, thus obviating undue wear at any one point.

As shown in Figs. 1 and 2 a tripping ring 34 is carried at the lower end of this mechanism by a plurality of posts 35 which extend upwardly through holes 36 in the flange 2 and into holes in the flange 14 of ring 13. This flange is provided with holes in which are mounted set screws 37 which are used to lock the posts 35 in adjusted position. The set screws 37 are provided with sockets 38 for the application of a screwdriver or other means for turning the set screws into place. Access to these set screws is gained by means of openings 39 in the shell 20. Attention is called to the fact that the tripping of the dogs 24 may be caused by engagement of any part of the lower face of ring 34 with the work or work holder, but that it is necessary for the ring to be pressed upwardly relatively to the thread cutters until the dogs are released from ring 26. The shell 20 is pressed downwardly and the springs 15 compressed by engagement of ring 27 with a part of the machine by which this tool is carried and operated. In a broad sense the shell 20 includes the outer sleeve, the ring 18 adjustably mounted therein, and the rings 26 and 27 secured to the latter by means of the screws 28. Though this shell includes several elements, it is functionally one element because the parts are secured together for simultaneous operation and to produce a single result.

In the edges of the flanges 2 and 14 are aligned notches forming slideways for the cam-carrying keys 40. These are secured to the flange 19 of the shell 20 by means of screws 41 passing through the flange and into the ends of the keys 40. This construction makes these keys, during operation, essen-

tially a part of the shell 20 and causes them to move with the shell during such operation. The keys are laterally notched as shown at 42 and each one carries on the face of this notch a cam 43 which cooperates with a cam groove 44 in one lateral face of the block 3. Therefore, when the dogs 24 are pressed inwardly, the shell 20 is released to move upwardly and in so doing, the cams 43, sliding in the cam slots 44, push the blocks 3 inwardly carrying the cutting members with them. When this construction is applied to a die, instead of a tap, the action of these cams is to move the cutting members outwardly instead of inwardly. The tripping element may be located around the thread cutters as here shown or may be centrally located. This is particularly desirable with a die.

When the set screws 33 are loosened and sleeve 18 turned with respect to the shell, it results in the shell being adjusted longitudinally, relatively to the shank 1. This adjusts the keys 40, blocks 3 and thread cutters 4. It is by this means that the thread cutters are adjusted to thread different sized openings, the amount of adjustment varying as much as $\frac{1}{16}$ of an inch or more.

The lower face of the flange 2 is provided with notches 45 which serve as guides for the blocks or chaser carriers 3. The blocks are beveled at 46 to correspond to the upward bevel in the notches 45. Notches 47 in the shell 20 correspond in size and location with the notches 45 and permit the blocks 3 to move outwardly in the shell. Keys 48 are rigidly mounted in grooves cut in a lateral wall of notches 45 and cooperate with grooves 49 in blocks 3 to hold these blocks from falling out of the tap head. The notches 49 are parallel with the edges 46 of the blocks so that the latter can slide freely with respect to both the upper faces of the notches 45 and the keys 48. Due to the relative angularity of these guides and the inclined faces of the screw threads, the threads of the thread cutters will be carried away from the completed threads at such an angle that there will be no scoring of the faces of those threads nor any breaking thereof by the withdrawing cutting members.

Operation

In use, the shank 1 of this device is applied to and secured in an appropriate rotating spindle and the parts are so adjusted that the tripping ring 34 will engage the work or a fixed stop and push the ring 22 upwardly far enough to move the dogs 24 in until ring 27 and with it ring 18 and shell 20 are released for upward movement under the influence of springs 15 pressing against the plate or ring 16. When the shell 20 is released for upward movement it carries with it the keys 40 carrying cams 43. These move vertically and thereby force the blocks 3 inwardly by

reason of the cam action. These blocks 3 are also given upward direction by reason of the co-action of the keys 48 and slots 49. Since the slots 49 are parallel with the inclined faces of the notches 45, the blocks 3 will slide in this direction. The angle of inclination of the direction of motion of the blocks is such that the threads of the cutting elements are moved away from the elements being threaded at such an angle that there will be no scoring or breaking of the threads. If the cutting end of one of the cutting elements 4 should be broken off for any reason, it is not necessary to throw away the entire die or tap but the broken cutting element may be moved outwardly so that it will extend downwardly to substantially the same plane as the lower ends of the other elements. By reason of the fact that these cutting elements extend upwardly for a considerable distance into the opening 12, it will be possible to make several such adjustments before one of the cutting elements is entirely used up.

By reason of the fact that the tripping mechanism operates so nearly absolutely the same place each time and the further fact that it is possible to make such minute adjustment of the parts to secure tripping of the mechanism and release of the thread cutting elements from the threads just cut, it is possible to cut a thread entirely into the inner face of a cap nut or the like or to the shoulder of a bolt, where the head and body of the bolt join. Also, owing to the fact that a plurality of dogs 24 are used in holding the shell downwardly, there is no tendency toward binding of the shank 1 and the shell when the latter is released for movement.

From the foregoing it will be seen that I have provided a novel device whereby the various objects set forth above may be accomplished and that the device is entirely automatic and accurate in its operation.

It will of course be understood that the specific description of structure set forth above may be departed from without departing from the spirit of my invention.

Having now described my invention, I claim:

1. In mechanism of the character described, a body comprising a shank and a flange, a shell surrounding the body and sliding on the flange, said shell having at its upper end a ring shaped abutment, locking dogs carried by the shank and engaging the said abutment to lock the shell in lowered position, and a ring slidable between the shank and shell and, in one position, engaging and withdrawing the dogs from locking position.

2. In mechanism of the character described, a body comprising a shank and a flange, a shell surrounding the body and sliding on the flange, said shell having at its

upper end a ring shaped abutment, locking dogs carried by the shank and engaging the said abutment to lock the shell in lowered position, springs within the shell and tending to separate the shell and flange by moving them longitudinally relatively to each other, a ring slideable between the shank and shell and, in one position, engaging and withdrawing the dogs from locking position, and a continuous abutment below said shell and connected to the slideable ring to actuate the same to release the dogs and permit relative movement of the body and shell.

3. In a thread cutting tool, a supporting member carrying a plurality of supports for thread cutters, thread cutters carried by the supports and adjustable with relation thereto, said supports having guiding grooves and actuating grooves, a shell laterally surrounding the aforesaid structure and carrying actuating keys, said keys cooperating with said actuating grooves for actuating the said supports to move them in radial planes toward and from each other, and means for holding the thread cutters and releasing them for adjustment.

4. In an implement of the character described, a body member, a shell surrounding and slideable longitudinally of the body member, a ring within the shell and slideable between the shell and body member, pins mounted in and slideable longitudinally of the body member, a substantially circular actuating member beyond the lower end of the shell connected to the pins and, when actuated, pushing the pins inwardly, said pins being connected to the ring and serving to move the same longitudinally when the actuating member is moved longitudinally of the implement.

5. In a structure of the character described, a body member having a shank, provided with laterally directed holes, locking dogs movable longitudinally in said holes and transversely of the shank, a shell movable longitudinally of the shank and engaged by the dogs, means for moving the shell longitudinally of the shank in one direction, means slideable on the shank to engage the dogs, and work engaging means connected to the last means to move the same and force the dogs to recede into the holes in the shank.

6. In a thread cutting tool, a supporting member carrying a plurality of supports for thread cutters, thread cutters carried by the supports, said supports having guide grooves and actuating grooves, a shell laterally surrounding the aforesaid structure and carrying actuating keys, said keys cooperating with said actuating grooves for actuating the said supports to move them in radial planes toward and from each other and means for adjusting the diameter of the thread cutting tool so as to regulate the diameter of the completed thread.

7. A tool of the character described having a shank, hollowed out at its forward end to form a receptacle for thread cutting elements, said shank having notches extending radially from the hollow, carriers in said notches carrying longitudinally adjustable thread cutting elements, guiding means to guide the carriers, and adjusting means for adjusting the positions of the carriers to vary the positions of the thread cutting elements.

8. In a tool of the character described, a body member, a sleeve reciprocating longitudinally thereof, a shell adjustably connected to the sleeve, thread cutting elements carried by the body member and movable diagonally in radial planes thereof, said thread-cutting elements being longitudinally adjustable, connections between the shell and thread cutting elements whereby axial movement of the former causes radial movement of the latter and means preventing or permitting relative adjustment of the sleeve and shell whereby the diameter of threads cut may be varied.

9. In a tool of the character described, a body member having a plurality of holding and actuating notches in an end thereof, guiding means within the notches arranged at an acute angle to the axis of the tool, chaser carriers mounted in the notches and guided thereby along substantially radial planes of the body member, said guiding means causing the chasers to move at an acute angle to the axis of the body member when moved along the said planes.

10. In a tool of the character described, a plurality of thread-cutting members, movable radially toward and from each other and diagonally of the axis of the tool, laterally movable carrying members holding and guiding the thread-cutting members in their movements toward and from each other and to which the thread-cutting members are adjustably secured, a shell movable longitudinally in one direction to actuate the carrying members in a direction transversely of the longitudinal dimension of the tool, resilient means to move the shell in the opposite direction, locking means to hold the shell in one actuated position, and tripping means movable longitudinally of the tool for releasing the locking means to permit the shell to move under the influence of the resilient means.

11. In a thread-cutting tool, a supporting member carrying a plurality of supports for thread cutters, thread cutters carried by the supports, said supports having grooves whereby they are guided diagonally of the supporting member and grooves whereby they are actuated to move in planes substantially radially of said member, a shell laterally surrounding the aforesaid structure and carrying actuating keys, said keys cooperating with said actuating grooves for actuating the said supports to move them in radial planes toward and from each other.

12. In a tool of the character described having a shank, hollowed out at its forward end to form a receptacle for thread cutting elements, said shank having notches extending 5 radially from the hollow, carriers in said notches to carry thread-cutting elements, thread-cutting elements carried thereby and extending into the hollow of the shank, guiding means to guide the carriers, and actuating means for moving the carriers toward and 10 from each other.

In witness whereof, I hereunto subscribe my name to this specification.

PAUL O. HECHT.
